(57) **CLAIM**

The ornamental design for a dock light, as shown and described.

DESCRIPTION

FIG. 1 is an overall perspective view of a dock light showing a first embodiment of my design;

FIG. 2 is a left side elevational view of the dock light of FIG. 1;

FIG. 3 is a right side elevational view of the dock light of FIG. 1;

FIG. 4 is a top plan view of the dock light of FIG. 1;

FIG. 5 is a bottom plan view of the dock light of FIG. 1;

FIG. 6 is a front elevational view of the dock light of FIG. 1; and

FIG. 7 is a rear elevational view of the dock light of FIG. 1.

FIG. 8 is an overall perspective view of a dock light showing a second embodiment of my design;

FIG. 9 is a left side elevational view of the dock light of FIG. 8;

FIG. 10 is a right side elevational view of the dock light of FIG. 8;

FIG. 11 is a top plan view of the dock light of FIG. 8;

FIG. 12 is a bottom plan view of the dock light of FIG. 8;

FIG. 13 is a front elevational view of the dock light of FIG. 8; and,

FIG. 14 is a rear elevational view of the dock light of FIG. 8.

The broken lines in the Figures are shown for illustrative purposes only and do not form part of the claimed design.
